United States Patent Office

Des. 181,250
Patented Oct. 22, 1957

181,250

COMBINED WASHING MACHINE AND WRINGER OR SIMILAR ARTICLE

Peter Eduard Geldhof and Robert E. Lake, Benton Harbor, Mich., assignors to Whirlpool-Seeger Corporation, St. Joseph, Mich., a corporation of Delaware

Application September 26, 1955, Serial No. 38,092

Term of patent 14 years

(Cl. D49—1)

FIG. 1

Des. 181,250

PAGE 2

FIG. 2

FIG. 3

Figure 1 is a front perspective view of a combined washing machine and wringer or similar article showing our new design;

Figure 2 is a rear perspective view thereof; and

Figure 3 is a top plan view thereof.

We claim:

The ornamental design for a combined washing machine and wringer or similar article, substantially as shown.
